DРИPPING DEVICE

Daniel M. Loughlin and Alrick B. Anderson,
Milwaukee, Wis.

Application August 22, 1933, Serial No. 686,309

6 Claims. (Cl. 299—1)

This invention relates to dripping devices, and more particularly to a type of dripping device that can be used by the public in the distribution and dispensing of liquids.

5 An object of the invention is to provide a device with means provided for dripping liquid, one drop at a time to moisten the fingers or hands of the user.

Another object of the invention is to enable a 10 person to moisten his fingers with a filtered liquid, without coming in contact with a moisture laden object, previously used by other persons, thereby eliminating the possible contact with disease germs.

15 Another object of the invention is to provide a means of forcing the dispensed filtered liquid that is not used, up into the supply reservoir, to be made to drip over again, until the entire supply is exhausted.

20 With the above, and other objects which will be apparent as the description proceeds, the invention consists of the following novel features and details of construction, to be hereinafter more fully described, illustrated in the accompanying drawings, and pointed out in the appended claims.

In the accompanying drawings,

Fig. 1 a top view of the device, showing the filler cap and air inlet.

30 Fig. 2 a front view of the entire device showing the tank arrangement,

Fig. 3 a partial cross-sectional view of the entire device,

Fig. 4 a side view

35 Fig. 5 a cross-sectional view of a conventional type of intake valve arrangement,

Fig. 6 a top view of the same valve arrangement,

40 Fig. 7 an inside view of the heating element support plate showing electrical contact posts,

Fig. 8 a cross-sectional view of the same heating element support plate,

Fig. 9 a side view of a mercury type of contact switch, actuated by a float, and

45 Fig. 10 an end view of the same switch arrangement.

Referring to the drawings in detail wherein like characters of reference denote correspond-

50 ing parts, the reference character 10 denotes the supply tank, with 11 indicating the liquid level in the tank. This level is displayed by means of a guage glass 12. There is a filler cap 13 with a semi-spherical recess in the bottom as indicated

55 by 14, an air intake at 15, and a drip-cock 17

which may be adjusted to regulate the flow of liquid to suit conditions.

The liquid dripping from the cock 17, enters a hopper 18, partly filled with filtering means, directly below the drip-cock 17. This hopper 18 has a pipe 19 leading into the lower storage tank 20, through intake valve 31, where the tank fills up to a level as indicated by the line 21. As the liquid level rises in the storage tank 20, a float 22 rises with it. This float 22 is guided by a rod 23 and has a vertical sliding motion. When a pre-determined liquid level has been reached, the float 22 contacts the pin 24 on the rod 23 and pushes the rod 23 upward in its guides 25 and 26 and by means of a link type arm 27 on the mercury switch support 28 which pivots on a pin 29 and is supported by a brace or bracket 30, tilts the mercury container 47 making a contact on posts 31a and 32.

This entire switch mechanism is enclosed in a 20 separate housing 33 closed tightly with a cover 34 in the manner shown in Fig. 10, or in some other manner equally as practical, to keep the contact parts above the level of the liquid.

There is an air tight tank 35 containing a 25 heating element 36 supported from a bracket 38 fastened to a plate 37, which is securely fastened to the wall of the tank 35. The plate 37 has two contact posts 39 and 40. Post 40 is connected directly with post terminal 31a and both 30 posts 39 and 40 are connected with the heating element 36. Posts 39 and 32 are the contacts for the positive and negative leads of electric current.

The operation of the device is as follows: 35

The liquid 46 in the upper tank 10 passes through the drip cock 17 into the hopper 18 in the lower tank 20, finding its way into this tank through the intake valve 31. When the liquid raises to a pre-determined height in tank 20, 40 the float 22 raises and pushes against pin 24 in rod 23. This raises rod 23 and its action with link 27 tips the mercury tube 47 to make contact with electric current. The current heats element 36 expanding the air in tank 35, forcing 45 same through pipe 44 into tank 20. This pressure forces the liquid in hopper at 45 into tube 16 carrying same up pipe 16 back into tank 10 against the semi-spherical recess 14. When the liquid level in tank 20 has gone down so that the 50 float 22 contacts pin 24 on rod 23 it pulls same down and tilts mercury switch 47 back to a normal position breaking electric current contact and allowing the air in tank 35 to recede to room temperature. As the air in tank 35 cools it con- 55

tracts and new air is drawn into the tank through intake valve 41 incased in a cover 43 having holes 42 to allow air to enter. The liquid when it leaves tank 20 through pipe 16, is prevented from coming out of the hopper 18 by the intake valve 31 which closes up against pressure, and the air in tank 35 is kept from escaping through intake valve 41 which is constructed similar to Fig. 5 and Fig. 6. However any other conventional type of intake valve may be used, as the method of operation of the entire unit as a unit would remain the same.

Having thus described our invention, what we claim and what we ask for Letters Patent from the United States is:

1. In a dripping device, means for containing and releasing a fluid in drip form, an open container for catching and containing the drip having an outlet with a check valve therein leading to a closed tank, and separable means for supplying gas pressure to raise the drip from the tank to the containing and releasing means for re-use, when the fluid in the tank reaches a predetermined level.

2. In a dripping device, means for containing and releasing a fluid in drip form, an open container for catching and containing the drip having an outlet with a check valve therein leading to a closed tank, and separable means for supplying gas pressure to raise the drip from the tank to the containing and releasing means for re-use, when the fluid in the tank reaches a predetermined level, said gas pressure supplying means comprising an auxiliary gas tank, communicating with said closed tank, and means in said auxiliary gas tank for heating said gas.

3. In a dripping device, means for containing and releasing a fluid in drip form, an open container for catching and containing the drip having an outlet with a check valve therein leading to a closed tank, and separable means for sup-

plying gas pressure to raise the drip from the tank to the containing and releasing means for re-use, when the fluid in the tank reaches a predetermined level, said gas supplying means comprising an auxiliary tank having valve means for entry of air thereinto, and means for heating said air when the fluid in the tank reaches the predetermined level.

4. In a dripping device, means for containing and releasing a fluid in the form of drip, an open container for catching and containing the drip having an outlet with a check valve therein leading to a closed tank, and means for heating a gas to place the same under pressure to force the fluid from the tank to the containing and releasing means for re-use, when the fluid in the tank reaches a predetermined level, comprising an electrical heater, switch means positioned on the exterior of the tank for operating said heater, and float means positioned in said tank for controlling said switch means.

5. In a dripping device, means for containing and releasing a fluid in drip form, an open container for catching and containing the drip having an outlet with a check valve therein leading to a closed tank, and means for supplying gas pressure to raise the drip from the tank to the containing and releasing means for re-use, when the fluid in the tank reaches a predetermined level.

6. In a dripping device, means for containing and releasing a fluid in drip form, an open container having filtering means therein for catching and containing the drip and having an outlet with a check valve therein leading to a closed tank, and means for supplying gas pressure to raise the drip from the tank to the containing and releasing means for re-use, when the fluid in the tank reaches a predetermined level.
